UNITED STATES PATENT OFFICE.

GUSTAF RENNERFELT, OF NEW YORK, N. Y.

FRICITION-GEARING.

1,017,910.

Specification of Letters Patent. Patented Feb. 20, 1912.

Application filed August 4, 1909. Serial No. 511,099.

To all whom it may concern:

Be it known that I, GUSTAF RENNERFELT, a subject of the King of Sweden, and a resident of the city of New York, in the county 5 of New York and State of New York, have invented certain new and useful Improvements in Friction-Gearing, of which the following is a specification.

My invention relates to improvements in 10 friction gearing, and its object is to make such gearing more applicable and better adapted to certain purposes and certain types of machinery than has heretofore been the case, and also to make it of higher efficiency 15 and so that it may be reliable in operation and cheap in construction.

I will describe my invention in the following specification and point out the novel features thereof in claims.

20 Referring to the drawing Figure 1 is a sectional side elevation of an electric motor equipped with a friction gearing constructed according to my invention. Fig. 2 is a sectional plan view, the section being taken on the line X—X of Fig. 1. Fig. 3 is a sectional plan view, the section being taken on the line Y—Y of Fig. 1. Fig. 4 is a sectional view of a detail referred to in the specification as a roller. Fig. 5 is a plan view of a 25 detail. Fig. 6 is a detail sectional view of the roller, and the part of the machinery to which the roller is attached. Fig. 7 is a sectional side view similar to Fig. 1, but 30 illustrating a modification of the invention.

35 Like characters of reference designate corresponding parts in all of the figures.

2 designates the shaft of the motor arranged to transmit rotary motion at reduced speed to the shaft 3, which is journaled in a bearing 4 fastened to the frame of the motor.

3 designates a yoke fastened to the shaft 3; and 6, 6 designate a plurality, preferably three, of studs fastened to the yoke.

45 7, 7 designate spherical rollers mounted loosely one upon each stud, and 8 designates a washer held on each stud outside of the roller.

9 designates a beveled track, stationary in 50 relation to the frame of the motor, and 10 designates a beveled wheel or bushing fastened to one end of the motor shaft. The track is beveled to the same angle as the bevel of the wheel, so that the side of the track 9 is parallel to the side of the wheel 10, as shown in dotted lines in Fig. 1. The

rollers, the track and the wheel are made of hard material, such as hardened steel or the like; the size of the aforesaid angle is such that it is substantially more than twice the 60 angle of repose for said materials. A shield 11 is located between the wheel and the parts proper of the motor, so that a chamber adapted to contain a lubricant is formed for the wheel and the rollers. The studs 6 are 65 hollow, and each is provided with a hole on its side shown in dotted lines in Fig. 1 and more clearly at 12 in Fig. 7. A wick 14 is shown in Fig. 7 for the purpose of conveying oil into the stud. In Figs. 1 and 6 the stud 70 is shown as provided with a nozzle 15 for the same purpose. The nozzle is directed in the direction of rotation of the roller 7 around the center line of the shaft 3 as indicated by the arrow in Fig. 6. During 75 the operation of the apparatus the pressure of the oil against the rotating nozzle will cause some amount of oil to flow through the hollow stud and the hole 12, so that the contact surface between the stud and the 80 center of the roller will become lubricated.

The other end of the motor shaft is mounted in a roller bearing arranged to sustain both radial and axial pressure and comprising a beveled track or race 16 mounted 85 on the shaft, a beveled race 17 mounted in the motor frame so that it can slide in axial direction, and a plurality, preferably four, of spherical rollers 18 interposed between the two races 16 and 17. Each roller 18 is 90 loosely mounted on a stud 19 which is secured to the flat rings 20, located at opposite ends of the rollers. A strong spiral spring 21 is placed between the race 17 and the plate 22, its pressure being transmitted 95 through the rollers 18, through the shaft 2, bushing 10 and rollers 7 to track 9. A shield 23 serves to protect this roller bearing from dust. A force applied to the spherical surface of a roller 18, whether such force is 100 due to axial or radial pressure from the shaft 2, will be directed through the center of the roller and will be balanced by a centrally directed force from the race 17 so that the roller 18 will have no tendency to 105 tilt. This is also the case with the spherical roller 7 which like the roller 18 constitutes the middle section of a sphere. The pressures applied to the roller 7 from the track 9 and bushing 10 are oppositely directed 110 through the center of the roller and are balanced, so that the roller will not be tilted.

nor crowded axially along its stud 6, and no part of the pressure from the spring 21 will be transmitted to the shaft 3.

The angle of bevel B of track 9 and bushing 10 is greater than twice the angle of repose, so that if the pressure exerted by the rollers 7 on the bushing 10 becomes abnormally great, due to inaccurate workmanship or the presence of dust, the bushing 10 together with shaft 2 and the aforesaid rollerbearing may recede against the action of the spring, and the abnormally excessive pressure on the bushing 10 will be relieved.

The rotary motion of the secondary shaft 3 may be transmitted in any preferred manner. A chuck 24 adapted to hold a drill (not shown) may be used, and the axial pressure on shaft 3 is then sustained on the rollerbearing 25 contained within the lateral bearing 4, and shown in plan view in Fig. 5.

The modification illustrated in Fig. 7 shows the bushing 10 of spherical form, the angle of the bevel of the track 9 is greater than in Fig. 1, the shaft 3 is provided with a coupling 26, and the bearing 25 is arranged to sustain pressure in a downward direction.

What I claim is:

30. 1. The combination of a beveled bushing, a track beveled with the same angle as the bushing, a plurality of spherical rollers between the bushing and the track, means for rotating the bushing, and means connected to the rollers for transmitting the rotation.
35. 2. The combination of a bushing, a track, a plurality of rollers having convex rolling faces between the bushing and the track, the side of the track being parallel to the side of the bushing, means for rotating the bushing, and means connected to the rollers for transmitting the rotation.
40. 3. The combination of a shaft, a plurality of studs supported by the shaft, a spherical roller mounted on each stud, a track in contact with the rollers, a bushing in contact with the rollers, the side of the track being parallel to the side of the bushing, means for pressing the bushing against the
45. 4. The combination of a bushing, a track, a plurality of rollers having spherical faces between the bushing and the track, yielding means for subjecting the rollers to balanced pressure between the bushing and the track, a frame surrounding the track, a shaft journaled in the frame and connection between the rollers and the shaft.
50. 5. The combination of a shaft, a beveled bushing at one end thereof, a beveled track, a plurality of convex rollers between the bushing and the track, means for pressing the bushing against the rollers, a beveled race on the other end of the shaft, a beveled
55. 6. race concentric with the first race, a plu-

rality of spherical rollers between the two races, means for rotating the shaft, and means connected to the first said plurality of rollers for transmitting the rotation.

6. The combination of a frame, a shaft, a thrust bearing at one end of the shaft arranged to slide in the frame, a spring between said bearing and the frame, a beveled bushing at the other end of the shaft, a beveled track, a plurality of spherical rollers between the bushing and the track, means for rotating the shaft, and means connected to the rollers for transmitting the rotation.

7. The combination of a shaft, a bushing thereon, a track, a plurality of rollers having spherical faces between the bushing and the track, means for applying power to the shaft, a second shaft, and means for transmitting power from the rollers to said second shaft.

8. The combination of a shaft, a plurality of studs supported from the shaft, a spherical roller mounted loosely on each stud, the stud being hollow and formed with a nozzle arranged to convey lubricant to the contact between the stud and the roller, a beveled bushing and a beveled track in contact with the rollers, and means for rotating the bushing.

9. The combination of a shaft, a plurality of hollow studs supported therefrom, a spherical roller mounted loosely on each stud, a beveled bushing and a beveled track in contact with the rollers, means for conveying oil into the studs, and means for rotating the bushing.

10. The combination of a frame, a shaft, a beveled race mounted on one end of the shaft, a beveled race arranged to slide in the frame, a spring between said race and the frame, a plurality of spherical rollers between the races, a beveled bushing mounted on the other end of the shaft, a beveled track, a plurality of spherical rollers between the bushing and the track, means for rotating the shaft, and means connected to said latter rollers for transmitting the rotation.

11. The combination of a shaft, a beveled bushing on one end of the shaft, a track, a plurality of rollers having convex rolling faces between the bushing and the track, means for pressing the bushing against the rollers, a frame surrounding the track, a second shaft journaled in the frame, and connection between the rollers and the second shaft.

12. The combination of a shaft, a beveled race mounted on each end of the shaft, a track around each of the races, a set of rollers having convex rolling faces arranged between each race and its track, a frame, and a spring between the frame and one of the tracks.

13. The combination of a shaft, a beveled race mounted on each end of the shaft, a track around each of the races, a set of rollers having convex rolling faces arranged between each race and its track, a frame, a spring between the frame and one of the tracks, a second shaft, and connection between said shaft and one set of the rollers.

14. The combination of a shaft, a beveled bushing thereon, a track, a plurality of rollers having spherical rolling faces arranged between the bushing and the track with their axis at an angle to the shaft, a beveled race on the shaft, a second race, and a plurality of spherical rollers between the two races.

15. The combination of a shaft, a beveled bushing thereon, a track, a plurality of rollers having spherical rolling faces between the bushing and the track, the diameter of a roller being greater than its length, a beveled race on the shaft, a second race, and a plurality of spherical rollers between the races.

Signed at New York in the county of 25
New York and State of New York this 31st
day of July A. D. 1909.
